CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS FOR DISTILLING COALS

Application filed October 27, 1924. Serial No. 745,951.

The invention relates to improvements in a process for removing and cracking the volatile substance from materials containing volatile and solid contents such as coals, shales, etc.

It is an object of the invention to provide a process adapted for this use in which a stream of oil or other carrying medium is first subjected to heat while travelling through a heating coil, into which oil at a point where it has obtained the majority of all of its necessary heat, finely pulverized coal is introduced. The coal is carried in the highly heated oil stream into an enlarged receiver where the volatiles leave the solid content thereof and undergo conversion, being withdrawn from said receiver for suitable condensation and collection.

More specifically, the invention contemplates a process where a stream of oil or other fluid medium is passed through an elongated coil and subjected to a cracking heat. To this highly heated oil containing the desired heat, I introduce finely pulverized coal, preferably beyond the heating zone and in a transfer line to be carried in said hot oil and to undergo a heat treatment while being transferred to an enlarged chamber where the vapors and gases from the heated coal separate from the carbon content while a substantial portion of the transfer oil likewise vaporizes. The removed vapor products undergo conversion in this chamber and are discharged to a reflux condenser where the insufficiently cracked vapors are condensed and the condensate thus produced returned to the heating coil to be heated therein and to receive additional supplies of pulverized coal. The vapors escaping from the reflux condenser are condensed and collected as low boiling point oils, while the carbon residue forming in the expansion chamber may be removed in any approved manner.

In the accompanying drawing, I have shown a diagrammatic apparatus capable of carrying out my process.

Referring now more particularly to the drawing, wherein like reference characters indicate corresponding parts, the character 50 A designates a furnace chamber of any ap-

proved type such as now used for cracking hydrocarbon oils. In this furnace, there is a continuous coil B fed by a line C having a feed pump D therein through which oil is passed under pressure. The furnace is heated by gas or any similar fuel preferably to a temperature sufficient to raise the oil to a liquid temperature of, say 850° F. Leading from the coil B is a transfer line E communicating with an enlarged insulating chamber F constituting a conversion or reacting chamber. This chamber may be of any desired size and additional heat may be applied thereto to compensate for heat losses in the chamber.

Leading to the transfer line E is a line G having a pump H therein to which pulverized coal is fed from a bin I through the line J. The coal may be bituminous, anthracite, peat, lignite or the like and is preferably of a fine subdivision, being of from one hundred to two hundred meshes per linear inch, although, of course, coarser or finer coals could be used. This coal, either in a dry state or when mixed with a small quantity of oil, gas, or other substances, is forced by the pump H into the transfer line E to be picked up and carried by the stream of hot oil passing therethrough to the enlarged chamber F. It will thus be seen that the coal is introduced to the oil after it has been heated but moves with said oil through a part of the transfer line so as to give a time element necessary to heat the coal particles. The coal particles in this oil then pass to the expansion chamber F where the volatiles separate from the carbon content of the coal. These volatiles, in the form of vapors and gases, pass out from the vapor transfer line K together with vaporized products from the oil into the reflux condenser L. The carbon residue collects in the chamber F. This residue may be either a substantially solid carbon free of residual oil or it may be part carbon and part residual oil. If part carbon and part residual oil, the latter is withdrawn through the line M continuously and not permitted to again enter the line C.

If a coke substantially free of oil is being 100

formed in the chamber F no residual oil need be continuously withdrawn.

The condensed vapors in the reflux condenser L collect in the leg N and are returned either by gravity or through the feeding pump D for repassage through the heating coil B. This condensate may be directly returned, or it may be introduced to a tank and from the tank fed to the pump D. The condensate therefore acts as the oil vehicle for carrying the fine coal in suspension, and after an operation has progressed a short time no extraneous oil need be used as the condensate produced from vapors derived from the coal alone will be in sufficient quantity to supply the necessary oil. The vapors pass from the dephlegmator L through a vapor line O to the final condenser P, the distillate being collected in a receiver Q while the uncondensable gases escape through the line R controlled by the valve S. The operation of this valve maintains the desired pressure throughout the stream, it being obvious that in operation a superatmospheric pressure of self-generated gases may be maintained throughout the system in excess of atmospheric. A valve T is also located in the vapor line K whereby pressure can be maintained in the coil B and reacting chamber F above atmospheric, and an atmospheric pressure or a reduced pressure maintained in the remaining portions of the apparatus.

In carrying out the process, oil or another liquid is first forced by the pump D through the heating coil B. As this oil, which is of a high temperature, passes through the line E, there is introduced to the same finely pulverized coal through the line G. The coal and oil travel to the conversion chamber F where vapors and gases are generated and where the hydrocarbon substances undergo cracking or conversion. If using an oil refluxed from vapors largely derived from coal, the transfer temperature of this oil may be 850° F. Heat may or may not be applied to the chamber F, but if this chamber is heavily insulated no heat need be used. The coal introduced to the oil if a bituminous coal is preferably of a fineness from one hundred to two hundred meshes per linear inch. The vapors generated are subjected to treatment in the reflux condenser L and the condensate produced is returned to the pump D for further passage through the heating coil and into this condensate additional supplies of coal are continuously introduced. The condensate, after a plant has been in operation for sometime, may be derived entirely from oils removed from the coal. The low boiling point oils are collected as distillate in the receiver Q while the carbon content of the coal collects in the reacting chamber F. A pressure of 120 pounds per square inch is preferably maintained throughout the apparatus and with such a pressure I have found that substan-

tial quantities of various oils can be obtained from a bituminous coal, which oils constitute excellent motor fuels and fractions capable of other uses.

The invention is also capable of use in removing oils from shale and the like in which event the non-carbonaceous content of the shale will collect in the enlarged chamber F.

Having thus described my invention, what I claim is:

1. In the art of recovering values from hydrocarbon sources, raising hydrocarbon liquid to a cracking temperature, in then bringing the heated liquid into the presence of hydrocarbon solids capable of destructive distillation and transferring heat from the hydrocarbon liquid and its vapors to the solids to cause distillation of the volatiles contained therein. 75

2. A distillation process consisting in heating a continuously advancing stream of hydrocarbon oil to a cracking temperature, in bringing said previously heated stream of hydrocarbon oil into heat transferring relationship with hydrocarbon solids to cause vaporization of the volatiles contained therein substantially by the heat of the hydrocarbon oil, and in recovering evolved vapors from the hydrocarbon oil and hydrocarbon solids. 80

3. A distillation process consisting in heating a continuously advancing stream of hydrocarbon oil to a cracking temperature, in bringing said previously heated stream of hydrocarbon oil into heat transferring relationship with hydrocarbon solids to cause vaporization of the volatiles contained therein substantially by the heat of the hydrocarbon oil, in subjecting evolved vapors from the hydrocarbon oil and hydrocarbon solids to reflux condensation, and in reheating reflux condensate to a cracking temperature to be brought into heat transferring relationship with the hydrocarbon solids. 85
